US0D1097966S

(12) **United States Design Patent** (10) **Patent No.:** **US D1,097,966 S**
(45) **Date of Patent:** **** Oct. 14, 2025**

(54) **WHEEL FOR AUTOMOBILE**

(71) Applicants: **Hyundai Motor Company**, Seoul (KR); **Kia Corporation**, Seoul (KR)

(72) Inventors: **Ju Ah Ha**, Gyeonggi-do (KR); **Hyo Sik Kim**, Gyeonggi-do (KR); **Tae Wook Choi**, Gyeonggi-do (KR)

(73) Assignees: **Hyundai Motor Company**, Seoul (KR); **Kia Corporation**, Seoul (KR)

(**) Term: **15 Years**

(21) Appl. No.: **29/898,422**

(22) Filed: **Jul. 27, 2023**

(30) **Foreign Application Priority Data**

Feb. 10, 2023 (KR) 30-2023-0004967

(51) **LOC (15) Cl.** **12-16**

(52) **U.S. Cl.** ..... **USPC** **D12/209**

(58) **Field of Classification Search**

USPC D12/209-213, 202-213; D15/10, 33; D21/561, 563
